UNITED STATES PATENT OFFICE

AUGUSTIN LÉON JEAN QUENEAU, OF FREJUS, FRANCE, ASSIGNOR TO EDMUND HEISCH
OF PARIS, FRANCE.

RETORT FOR THE CARBONIZATION OF SOLID FUELS.

Application filed November 27, 1923. Serial No. 677,248.

to all whom it may concern:

Be it known that I, AUGUSTIN LÉON JEAN QUENEAU, citizen of the Republic of France, residing at Mines de Bozon, Frejus, Var, France, have invented certain new and useful Improvements in Retorts for the Carbonization of Solid Fuels, of which the following is a specification.

This invention relates to horizontal or practically horizontal retorts employed in the carbonization of solid fuels such as for instance wood, coal, shales, lignite, etc. These retorts are usually cylindrical and contain a conveyor device for transporting the material, constituted by a simple or multiple Archimedean screw. This screw or worm is so arranged that at the top of the retort is left, between the worm itself and the wall of the retort, a space affording free passage to the gases which are generated during the treatment of the fuel. Some of the said gases, becoming dissociated on contact with the hot wall of the retort, give carbon or retort coal which settles on the wall and thus reduces the above mentioned space which is very quickly completely choked up. The gases can then only escape by following the path of the solid material, that is to say, the spires of the worm. It is necessary to scrape the deposit very frequently in order to remedy the defect in question, and this fact is a serious drawback.

According to the present invention, a retort is provided in which this disadvantage is eliminated, such retorts comprising for the purpose two cylinders with parallel horizontal axes secant along two generatrices and communicating by all the zone common to each of them. The conveyor device is constituted by a combination of two shafts, the axes of which are situated respectively a little below the axes of the above mentioned two cylinders; the said shafts carry blades which pass between each other from one shaft to the other, and leave between them free spaces through which pass the gases generated, on their way to the outlet.

These retorts comprise moreover a device for introducing the fuel, and a device for discharging the residues, designed so as to avoid as far as it is possible introduction of the outside air into the apparatus when they are working by a continuous process.

In the accompanying drawings given by way of example, Figure 1 is a cross-section

of the retort according to the invention on the line A—B—C—D of Figure 2.

Figures 2 and 2^a show after joining at the lines X—X, a horizontal longitudinal section.

Figure 3 shows in perspective one of the parts of the devices for feeding and for discharging the fuels.

Figure 4 shows in perspective the retort on a smaller scale.

Figures 5 and 5^a show, after joining at the lines X—X, a horizontal section of a retort in which the two parallel shafts which produce the driving of the materials, are deformable.

Figure 6 is a cross-section of the said retort on the line X—X of the Figure 5.

1 is the body of the retort having in cross-section the shape of an eight (Figure 1). In the interior of each of the two cylinders which constitute the said retort, is arranged a shaft 2, 2_a, the axis 3, 3_a of which is a little below the axis 4, 4_a of each cylinder. Each shaft 2, 2_a is made in one piece and constituted for instance by a steel tube, into the ends of which are screwed, with screw threads of a direction opposite to that of the movement of rotation of the shafts, short pieces of shafting of a smaller diameter intended to form journals. These tubes are made in one piece, and no pin or rivet passes through them, that would be liable to produce the formation of cracks through which the outside air could pass into the retort. The fixing of the above mentioned pieces of shafting on each steel tube is effected along conical bearing surfaces, which ensures air-tight joints between these parts. Suitable packing is provided at the ends of the cylinders forming supports for the shafts 2, 2_a, so as to prevent any outside air from passing in along the said shafts.

The tubular shafts 2 and 2_a having thus been mounted so as to avoid any introduction of the outer air into the retort, a cooling current of air may be circulated in the interior of the said tubes.

The shafts 2, 2_a have inside the retort a polygonal cross-section (Figure 1) so as to enable the blades 5 to be put in place and secured, the said blades being integral with polygonal elements 6 which fit exactly on the shafts 2 and 2_a. These blades are put in place on each shaft in such a manner that

their axes should be, from one blade to the next one, at a certain uniform angle, for instance 90° (Figures 1 and 2) and so that, from one shaft to the other, the blades of a shaft come between the blades of the other shaft having the same direction, in the zone common to the two cylinders. If the four successive blades of the shaft 2 are called $5^1, 5^2, 5^3, 5^4$, and the four successive blades of the shaft 2_a , $5_a^1, 5_a^2, 5_a^3, 5_a^4$, a blade 5_a^1 will come, in the zone common to the two cylinders, between two consecutive blades 5^1 (Figure 2). The end blade of each shaft, at the feed side, strikes against a shoulder of the shaft, whilst the end blade at the discharge side is locked in any suitable manner, for instance by set screws 7, 7_a .

The shafts 2, 2_a are rotated in the opposite direction (see the arrows in Figure 1), at the same speed, by means of any desired suitable mechanism comprising for instance a pinion 8 connected to a motor, a pinion 9 engaging with the latter and keyed to the shaft 2, and two helical pinions 10, 10_a of the same diameter ensuring the driving of the shaft 2_a . 11 is a supporting frame and 12 thrust bearings taking up the thrust reaction exercised on the blades 5 by the fuel moving in the retort.

30 The introduction of the solid fuels takes place at one of the ends of the retort, the right hand one in the drawing. A conduit 13 opens into the zone common to the two cylinders, the said conduit containing a rotating part 14 or a plug provided with a recess 15. When the plug 14 is in the position shown in Figure 1, the materials which are placed above the said plug pass into the recess 15. The plug, in continuing to rotate, drives a given quantity of fuel, without however introducing any material quantity of the outside air, and when it is in the position diametrically opposite that illustrated, it discharges its load into the conduit 13.

45 At the opposite end of the retort is a discharge conduit 16 which contains an identical device, so that a regular discharge of the solid residues may be made without introduction of the outer air through the outlet orifice.

Figure 2 shows the recess 15' of the plug 14' of the above mentioned discharge or evacuation device.

50 One or more pipes 17 for the escape of the gases generated by the carbonization of the materials, are arranged at suitable points of the retort (Figures 2 and 4). These various pipes open into a general collector or manifold 17' which guides the gases towards the points where they are utilized.

The working of the apparatus is as follows:

55 The materials introduced through 13 at regular intervals and in constant quantities, drop to the bottom of the retort and have

the tendency to quickly fill the retort up to a certain level, a regulation of the speed of the movable elements of the apparatus avoiding the said level being exceeded. The blades 5 carried by the shafts 2 and 2_a , which, owing to their oblique position, act as an Archimedean screw, ensure regular transport of the material along the axis of the retort, and moreover tend constantly to move the said material away from the zone common to the two cylinders in order to bring it in contact with the outer walls of the retorts, which are the nearest to the furnace. The arrangement of the blades, as shown in Figures 1 and 2, ensures their mutual cleaning, and at the same time provides, above the level of the material being treated in the retort, wide empty spaces where the gases freely circulate in their passage towards the outlet orifice or orifices 17. The carbonized materials drop finally by gravity into the discharge conduit 16.

In the construction shown in Figures 5 and 6, the two parallel shafts are deformable. To that end, each of them comprises a cylindrical portion 18 passing through the cover 19 of the retort which thus forms a support and a bearing for it. In the interior of the retort, each shaft has a circular portion 20 of a large diameter and finally a cross-shaped portion 21.

Two or more shaft portions 22, 23 are arranged in the extension of the portion 21, and finally an end piece 24 comprising: a cross-shaped portion 25, a collar 26 and a cylindrical portion 27, engages with its portion 27 with a recess in the cover 28 of the retort, with the interposition of stops 29. A tight joint is thus secured.

The various portions 21, 22, 23 and 25 of each shaft are of such a length relatively to the length of the retort, that a clearance is left between them as shown at 30.

The coupling of the shaft pieces 21, 22, 23 and 25 is ensured by means of rings 31, 32 and 33 of suitable length, in the interior of which are provided grooves 34 owing to which they may be fitted with a certain play on the ribs 35 of the cross-shaped parts 21, 22, 23 and 25.

115 This method of coupling is of the kind used in rolling mills for driving the top cylinder by means of wobblers.

Other rings 36 having the same shape as the rings 31, 32 and 33, are also arranged on the parts 22 and 23, between the rings 31, 32 and 33.

120 Each of the rings 31, 32 and all the rings 36 comprise a blade 37, and the keying of all rings on one and the same shaft relatively to each other, is such that the blade 37 of a ring is at 90° relatively to the preceding one and to the following one, the whole of the blades 37 of one and the same shaft having diagrammatically the shape of 125

5 a screw. Finally, the blades of one of the said shafts intersect, during the rotation of the shafts, the path described by the corresponding blade of the opposite shaft, but without ever meeting it.

10 Owing to the construction and to the method of erection described, the shafts in rotating may become deformed in the interior of the retort, without breaking, so as to fit the shape of the lower bottom of the retort, the weight of the said shafts always tending to keep the blades in contact with the lower wall of the retort and thus preventing the retort carbon from accumulating.

15 What I claim is:

20 1. A retort comprising a casing, a rotary conveyor mounted therein, said conveyor constituted by a number of aligned non-circular shaft sections and rings encircling the shaft sections, and having non-circular openings loosely receiving the non-circular sections, some at least of said rings being provided with conveyor blades and at least some of said rings serving to couple said

25 shaft sections.

2. A retort comprising a casing, a rotary conveyor mounted therein, said conveyor formed of a number of aligned shaft sec-

tions, selected portions of said shaft sections being of non-circular form and rings encircling said shaft sections and having non-circular openings loosely receiving the non-circular portions, said rings provided with conveyor blades, at least some of said rings serving to couple the shaft sections together, whereby to insure movement together of the rings and shaft sections yet permit movement due to expansion.

3. A retort comprising a casing, a rotary conveyor shaft mounted therein with its axis below the axis of the casing, said shaft being formed by a number of aligned cross-shaped sections, and rings encircling the shaft and having cross-shaped openings loosely receiving the cross-shaped sections of the shaft, said rings being provided with conveyor blades and at least some of said rings serving to couple said shaft sections whereby the shaft may be deformed and accommodate itself to the shape of the lower portion of the retort casing to prevent the retort carbon from accumulating on the same.

In testimony whereof I hereunto affix my signature.

AUGUSTIN LÉON JEAN QUENEAU.
